IMPACT RELEASE MECHANISM FOR FIRING PIN

Max Earl Eggman, Fort Wayne, Ind., assignor to The Magnavox Company, Fort Wayne, Ind., a corporation

Application November 16, 1954, Serial No. 469,099

4 Claims. (Cl. 102—73)

This invention relates to a multi-direction impact release mechanism for firing pin or member for initiating a series of events such as detonating a charge as in a torpedo and other missiles including bombs, mortars, grenades, etc. Thus, the invention has other uses, for example, to turn on lights or blow up classified equipment in the event of an airplane crash; release a parachute from a drop package upon landing to prevent the parachute from dragging the package; or release a signalling device from a package dropped free fall from an airplane.

The principal object of the invention lies in the structure of such mechanism wherein a firing pin or initiating member may be released upon impact from any direction, whether the energy transmitted by the impact is axial, transverse, or a combination thereof. Further advantages inherent in the invention reside in the fact that the complete assembly may be extremely small, containing few parts, many of which may be produced on a punch press, and simple to lock up and release.

The invention generally embodies a multi-sided energy transmitting housing such as to effect release of the initiating mechanism contained in the housing upon impact from any direction. Said mechanism may be primarily rendered inoperative for safety by a removable arming pin, which will then permit the telescoping of a barrel within a sleeve upon an applied impact force, the telescoping of said members thus effected releasing a locking element which will thereupon permit a spring loaded firing pin or initiating member to stab a primer or close an electric impulse circuit or otherwise initiate a chain of action.

The full nature of the invention will be understood from the accompanying drawings and the following description and claims:

Fig. 1 is a central vertical section through the mechanism, showing it in inoperative or safety position, with parts thereof in elevation.

Fig. 2 is a section taken on the line 2—2 of Fig. 1.

Fig. 3 is the same as Fig. 1 showing the mechanism in released firing position.

In the drawings there is shown by way of example, an impact release mechanism for a firing pin or initiating member adapted to initiate a series of events through applied impact force in any direction, and comprising a multi-sided housing having an upper cylindrical portion 10 secured in mating relation to a lower cylindrical portion 11. The upper portion 10 terminates in a conical camming head 12 having an axially extending boss 13. The lower cylindrical portion 11 terminates in an inwardly and downwardly disposed conical base 14 having its end portion open at 15.

Mounted within the housing axially of the cylindrical portion thereof, with one end bearing against the base portion about the opening 15, there is an outer sleeve 16 in which a cylindrical barrel 17 is slideably mounted. The barrel 17 carries at the lower end thereof a primer 18 or any other detonating medium, such as an electrical switch, which, upon impact by the firing pin or mem-

2

ber will set off an explosive charge or the like. Slideably mounted within the barrel 17, there is a firing pin 19 spring loaded by the compression spring 20. Said firing pin is provided with a conical plunger 21 adjacent to but spaced from the impact extension thereof at 22. The load spring 20 has one end bearing against a shoulder formed toward the upper end of the barrel, the other end of said spring bearing against the plunger 21.

The barrel and sleeve are locked against telescoping by 10 a locking leaf or latch member 23 pivotally mounted at 24 in a slot formed in the portion of the barrel adjacent the conical head 12 of the housing. Said latch member is held in latching position to prevent telescoping of the barrel and sleeve by an arming pin 25 removably extending through the boss 13 of the housing into position to be engaged by the free end of said latching member. When said latching member is restrained through engagement with the arming pin, it will be engaged by the free end of the sleeve 16 to prevent telescoping movement thereof. When the arming pin is removed, such telescoping movement will be permitted upon an impact force applied against the housing from any direction.

Said barrel is provided with a lateral opening 26 normally adjacent the impact extension 22 and plunger 21 of 25 the firing pin, in which a locking ball 27 is positioned, said ball being normally confined in said opening between the inner wall of the sleeve, the impact extension 22, and plunger 21, to lock the firing pin 19 in its spring loaded position.

30 The sleeve 16, just beyond the ball confining portion thereof is provided with an enlarged cavity 28 for permitting lateral movement of the ball upon telescoping of the sleeve and barrel to release the spring loaded firing pin for firing impact with a primer 18 or the like, as shown in Fig. 3.

In operation, the mechanism is set on safety as shown in Fig. 1. In this arrangement of the assembly, the mechanism will be inoperative and therefore provide a safety factor. For cocking the mechanism preparatory 40 to firing a charge upon applied impact force against the housing from any direction, the arming pin 25 is removed. Upon such impact the latch member 23 will be swung or tilted about its pivotal mounting free of restraining engagement with the barrel 16, as shown in Fig. 3. Said sleeve will then be permitted to telescope in the barrel to a position wherein the locking ball 27 will be forced laterally into the cavity 28 by the beveled surface of the plunger 21 under tension of the load spring 20. Being 45 thus freed the load spring is released to force the firing pin against the primer 18 or other charge detonating member whereupon the charge will be fired.

If the impact is along the axis of the barrel, as in Fig. 3, the barrel and sleeve will be directly telescoped by the 55 forces of deceleration. If the impact comes at right angles to the axis of the barrel, the barrel and sleeve will be thrown to one side of the housing and telescoped by the camming action of one of the conical surfaces of the head portion 12. If the impact is applied at any other 60 angle, the barrel and sleeve will be telescoped by a combination of the above two actions resulting in release of the spring loaded firing pin to detonate a charge.

The invention claimed is:

1. An impact release mechanism for an action initiating member comprising a housing having a cylindrical portion and a camming end portion, a telescoping sleeve and barrel mounted in said housing axially thereof to bear against the end portions thereof, a spring loaded action initiating member slideably mounted in said barrel movable under spring pressure to strike an initiating element, a locking ball mounted in a lateral opening provided in the wall of said barrel and retained therein by said sleeve

to lock said member with its load spring under compression, an arming pin extending through said housing into the free end of said barrel, and a latch pivotally and freely mounted on said barrel and restrained by said pin in the way of movement of said sleeve to prevent telescoping movement between said barrel and sleeve, said latch being movable by said sleeve out of locking position to permit telescoping upon removal of said arming pin, said sleeve having an adjacent cavity for receiving said ball and releasing it from locking engagement with said member upon said telescoping movement to thereby permit said member to be forced under its spring loading to action initiating position.

2. An impact release mechanism for an action initiating member, comprising a housing having angularly disposed end portions, a telescoping sleeve and barrel normally mounted in said housing axially of said end portions to bear thereagainst, a spring loaded initiating member slidably mounted in said barrel movable under spring tension to strike an initiating element, a locking member movably mounted in said barrel and retained therein against said initiating member by said sleeve for holding said loading spring under compression, a freely movable latch member operatively associated with said sleeve and barrel for locking them against telescoping movement, and an arming pin positioned to engage said latch member for holding it in latching position to be disengaged therefrom to permit movement thereof to its unlatching position, said sleeve being movable relative to said barrel, said latch member, and said locking member to move said latch member and release said locking member upon an impact force directed against said housing.

3. An impact release mechanism for a firing pin comprising a housing having an angularly disposed end portion, a telescoping sleeve and barrel mounted in said housing with one end of said barrel engaged centrally of said end portion and the opposite end of said sleeve bearing against the opposed end portion of said housing, whereby upon an impact force being applied against the side portion of said housing said barrel will be cammed by said end portion to telescoped position, a spring loaded firing pin slideably mounted in said barrel movable under spring pressure to strike a detonating element, a locking member mounted in a lateral opening provided in the wall

of said barrel and retained therein by said sleeve against said firing pin with its load spring under compression, and a releasable latch associated with said sleeve and barrel normally locking them against said telescoping movement and permitting said movement upon the release and subsequent displacement thereof, said sleeve being adapted to provide said displacement of the latch and having an adjacent cavity for receiving said locking member and releasing it from engagement with said pin upon said telescoping movement to thereby permit said pin to be forced under its spring loading to firing position.

4. An impact release mechanism for a firing pin comprising a housing having an angularly disposed end portion, telescoping sleeve and barrel members mounted in said housing with one of said members in axial engagement with said end portion and the other said member in engagement with the opposite side of said housing, a spring loaded firing pin slideably mounted in one of said members movable under spring pressure to strike a detonating element, a latch operatively associated with said members and pin for retaining said pin in spring loaded position, said latch being releasable from said pin retention upon telescoping movement between said members to thereby permit said pin to be forced under its spring loading to firing position, and a second releasable latch operatively associated with said telescoping members normally latching them against telescoping movement and displaceable to permit said telescoping movement upon being released, said second releasable latch being adapted to be displaced by said sleeve member subsequent to its release.
